UNITED STATES PATENT OFFICE.

HENRY L. CHARLES, OF BUTTE, MONTANA.

ORE REDUCING AND REFINING FURNACE.

1,348,151.

Specification of Letters Patent.

Patented Aug. 3, 1920.

Application filed November 6, 1917. Serial No. 200,614.

To all whom it may concern:

Be it known that I, HENRY L. CHARLES, a citizen of the United States, residing at Butte, in the county of Silver Bow and State 5 of Montana, have invented certain new and useful Improvements in Ore Reducing and Refining Furnaces, of which the following is a specification, reference being had thereto in the accompanying drawing.

10 My invention relates to improvements in ore reducing or refining furnaces and has for one of its principal objects to provide means for bracing the roof of the furnace without the use of buck-stays, rods and 15 similar devices heretofore generally employed. My invention also contemplates means for protecting that part of the furnace where the ore is admitted and various other features hereinafter more particularly 20 set forth.

In the accompanying drawings I have illustrated in Figure 1 in vertical cross-section with parts broken away a suitable application of my invention. Fig. 2 is a longitudinal section on the line 2—2 of Fig. 1, 25 with parts broken away, and Fig. 3 is a plan view on the line 3—3 of Fig. 1, parts being broken away, the monolithic material not being shown.

30 4 indicates a suitable foundation, and 5—6 side walls of the furnace. 6' indicates the side wall of the next furnace arranged parallel in the usual manner. According to a preferred embodiment of my invention, 35 the foundation 4 is preferably continued upwardly between the walls 5—6' of adjacent furnaces forming an abutment wall 7 as shown, thereby providing a suitable platform such as 8 for the convenient operation 40 of the furnaces. This abutment wall 7 may be suitably reinforced by steel girders such as 9 and is preferably provided at opposite sides with recesses or pockets 10 into which the ends of the bolts 11 may project, said 45 bolts having heads 12 adapted to engage the plates 13 of suitable water cooling sections or boxes hereinafter more fully referred to. The plates 13 are in turn reinforced or braced by the webs of steel 14 which in turn 50 bear against the walls of the water circulating chambers 15 as shown.

The roof of the furnace preferably consists of a double row of bricks 16—17 topped

with a suitable covering of monolithic material or other suitable refractory material 55 34. The water circulating chambers 15 are preferably secured upon the outer margins of the lower row of bricks and the upper layer of bricks and monolithic material preferably extend between the same as shown. 60 These water circulating boxes are preferably provided with an interior passage 18 sufficient to allow clearance for the nozzles 19 to feed the ore from the hoppers 20. 21 indicates suitable uprights for supporting 65 the superstructure 22, and 23—23' indicate suitable hand controls for regulating the flow of the ore, said controls being preferably located above and below the pivotal or ball and socket connections 24. 70

From the foregoing it will be seen that as the furnace heats up, the nuts 25 may be loosened to allow for the expansion of the arched roof, the abutment wall 7 serving as a brace between the roofs of adjacent furnaces, thus providing a convenient, accessible and the strongest kind of construction for taking care of the expansion of the arched roofs without the necessity of using buck-stays, rods and similar appliances 80 requiring attention at numerous places and which do not give proper support to the side walls of the furnace. Suitable inlets and outlets such as 26—27 may be provided for each of the water boxes at the sides of the 85 furnaces to provide for the proper circulation of water and these boxes are of course preferably connected in any suitable manner so as to provide for a continuous circulation throughout the entire sets of boxes 90 employed.

Referring now more particularly to Fig. 2, it will be observed that at the front of the furnace instead of employing the usual brick stack, or flue I have illustrated a suitable 95 water jacketed flue or stack indicated by the reference character 28, the water circulating therein being in communication with the boiler 29 from which it may be used in the operation of the systems as may be desired. 100

The nozzles 19 may be water jacketed, that is to say, the tube 30 preferably ends at 31, and the nozzle 19 is preferably formed of concentric tubes 19—19' between which water may be circulated through the inlets 105 such as 32—33.

Of course it will be understood that various modifications may be made in the construction and arrangement of parts without departing from the spirit of the invention as claimed.

I claim:

In combination with a furnace of the class described, ore inlets at the sides of said

furnaces, and hollow water circulating boxes through which said ore inlets may be shifted. 10

In testimony whereof I hereunto affix my signature in the presence of two witnesses.

HENRY L. CHARLES.

Witnesses:

ANNA F. DUFFY,
THOMAS A. HILL.
